SHOE SEWING MACHINE

Stevenson A. Dobyne and John C. Dobyne, St. Louis, Mo.

Application September 27, 1934, Serial No. 745,692

19 Claims. (Cl. 112—34)

This invention pertains to shoe sewing machines, and more particularly to the type of machine known as the McKay stitcher.

One of the objects of this invention is to provide a machine of this type of simplified construction and operation;

Another object is to provide improved stitching mechanism for such a machine;

Another object is to provide improved driving means for such a machine whereby a variation in speed may be obtained in a simple manner;

Another object is to provide improved mechanism adapted to measure a length of thread for each stitch in accordance with the thickness of the work;

Another object is to provide improved waxing means for such a machine.

Further objects will appear from the following description when taken in connection with the accompanying drawings, in which:

Figure 1 is a side view of a machine embodying this invention;

Figure 2 is a detail section on line 2—2 of Figure 1;

Figure 3 is a detail view of a section of the driving pulley;

Figure 4 is a detail vertical section along the axis of a countershaft;

Figure 5 is an enlarged front view of the sewing head;

Figure 6 is a side view of Figure 5 as seen from the opposite side from Figure 1;

Figure 7 is a detail of Figure 6;

Figure 8 is a detail of Figure 5 in which parts have been omitted and in which other parts are shown in section for clarity in illustration;

Figure 9 is a detail section taken on line 9—9 of Figure 5;

Figure 10 is a detail similar to Figure 8 but showing the feeding mechanism;

Figure 11 is an enlarged vertical section of the wax pot;

Figure 12 is a detail front view of Figure 11; and

Figure 13 is an enlarged detail of the feed cam.

Referring now to the drawings, 1 designates a supporting standard of appropriate form having mounted thereon a bracket 2 carrying a driving motor 3 of any suitable type. The motor 3 is connected by a belt 4 with a pulley 5 running loosely on a shaft 6 fixed in the standard 1. The pulley 5 has attached thereto a driving pulley 7 of special form which will be described in detail hereinafter, which driving pulley 7 is connected

by a round belt 8 with a pulley 9 running loosely on the main shaft 10 of the sewing head.

The standard 1 has mounted at the top thereof and so as to project forwardly a supporting plate 11 which carries the sewing head. Formed or mounted on the plate 11 are bearing brackets 12 and 13 in which the main shaft 10 is journaled. A releasable clutch 14, the operation of which will be described later, is arranged to connect the pulley 9 with the shaft 10 to drive the latter when required for sewing.

Needle bar mechanism

The bracket 13 has a forwardly projecting head 15. Slidably mounted in guides in the head 15 and the plate 11 is a needle bar 16. The needle bar is guided for vertical movement in the guide openings in the head 15 and the plate 11, and is maintained against rotation by a clamp 17 secured to the needle bar and having spaced ends 20 slidable along an upright guide rod 18 secured in the plate 11. Where the needle bar passes through the head 15 it is engaged by a friction plug 19 lodged in a bore in the head 15 and pressed by a spring 20 against the needle bar, 25 said spring being retained by a screw 21. This serves to frictionally retain the needle bar in whatever position it may be until acted upon by the driving mechanism.

Mounted on the needle bar 16 is a slide 22 30 which may slide vertically along the bar. The downward movement of this slide is limited by a stop 23 clamped to the needle bar so as to be engaged by the slide upon its downward movement. A washer 24 of leather, or the like, provides a buffer between the slide and the stop.

The rear face of the slide 22 has a groove 25 adapted to receive a roller 26 on a crank pin 27 projecting from the face of a crank disk 28 fixed on the shaft 10. The shape of the groove 25 is 40 illustrated in Figure 8. This groove has a certain portion thereof indicated at 250 which is circular and concentric with the shaft 10 when the crank pin 27 is in its lowermost position, as shown in Figure 8. This shape provides, therefore, that there will be a pause in the movement of the needle bar at the lowermost point of its stroke. This pause is provided in order that the thread may be engaged in the hook of the needle by the action of the whirl. The direction of rotation 50 of the shaft 10 is indicated by the arrow in Figure 8. This gives the slide 22 a reciprocating motion along the needle bar with a pause at its lowermost position.

Adjustably clamped to the needle bar above the 55

slide 22 is a collar 29 fixed by a set screw 30 or other suitable means. This collar carries a stud 31 on which is pivoted a latch member 32 adapted to engage an upstanding abutment 33 on the slide 5. 22. The latch member 32 has a rearwardly extending arm 34 held by a spring 35 against a stop pin 36. The latch 32 and the abutment 33 are preferably constructed of hardened steel in order to withstand the wear occasioned by their relative 10 movement. Pivoted on a shaft 37 journaled in a bearing 38 on the head 15 is a cam 39 whose lower cam portion extends into the path of the arm 34 as the latter rises with the needle bar. A spring 40 on the shaft 37 is arranged to tension 15 the cam 39 so as to retain it against a stop 41. By movement of the stop 41, as will be described hereinafter, the cam 39 may be rotated on the shaft 37. By such rotation on account of the shape of the lower edge of the cam 39, the distance traveled by the arm 34 before engaging the cam may be varied. When such engagement 20 takes place the continued rise of the needle bar 16 causes the latch 32 to rotate on its pivot 31 whereby said latch is carried forwardly to disengage it from the abutment 33. This releases the needle bar from the slide 22. The needle bar is now retained by the friction device 20 while the slide 22 may rise further in accordance with the action of the crank 27. 25

30 It will be seen that by variation of the height of the abutment 41 the cam 39 may be operated to vary the height of the up-stroke of the needle bar 16. The down-stroke of the needle bar, however, is always limited to a constant lowermost position by engagement of the slide 22 with the stop 23. Thus the needle is always moved downwardly to a constant position in order to receive the loop of the thread while the height of the up-stroke may be varied in accordance with the 35 thickness of the work as will be described more fully presently.

A cast-off 138 engaging the needle in the usual manner has a shank extending upwardly through a vertical bore in the needle bar 16. The upper end of this shank is clamped to an arm 140. This arm has a vertical bore slidable on a rod 141. Said rod is in turn slidable in a sleeve 142 adjustably mounted in the plate 11 and secured by a set screw 143, or other suitable fastener. The sleeve 142 is provided with a frictional retaining device 144 similar in all respects to the device 19, 29 already described. The rod 141 is guided in the sleeve 142 at its lower portion and at its upper portion in a vertical bore in the stop 23. The 40 upper end of the rod has secured thereto a collar 145 provided with a stud adapted to receive the hooked end of a spring 146. The lower end of this spring rests in a socket in the arm 140. The spring 146 acts to depress the arm 140 against an adjustable stop collar 147 secured to the rod 141. Another adjustable stop collar 148 is secured to said rod just below the stop 23. 45

The movement of the cast-off 138 is controlled by movement of the needle bar 16. The spring 146 retains the arm 140 depressed against the collar 147 and also provides a yielding abutment for the cast-off in case the latter strikes an obstruction in descent. As the needle bar descends the stop 23 engages the collar 148 and moves the rod 141 downwardly in its guides, carrying with it the cast-off 138. As the needle bar rises again, the frictional retainer 144 retains the rod 141 in its lower position until the needle brings the loop of thread in its hook up under the cast-off and 50 through the loop of the previous stitch. There-

after the stop 23 engages the collar 145 and the cast-off moves upwardly with the needle bar.

Thread measuring mechanism

A presser foot 42 is mounted on a presser bar 43 which is also vertically slidable in guides in the plate 11 and the head 15. The upper end of the presser bar 43 carries a bracket 44 in which is adjustably mounted the stop 41. This stop may have the form of a screw threaded in the bracket 44 for adjustment and fixed by a jam nut 45. It will be seen, therefore, that by elevation of the presser bar 43 the stop 41 is elevated and the cam 39 is moved accordingly.

The raising of the presser foot is accomplished by a cam 46 on the main shaft 10. Loosely pivoted on a shaft 47 journaled in the bracket 43 is a bell crank, one arm 48 of which carries a roller 49 engaging the cam 46. The other arm 50 of said bell crank carries an adjustable abutment 51 engageable with a lifting dog 52 which operates to lift the presser bar 43. The dog is pivoted at 53 to a collar 54 slidable on the presser bar 43. The inner end of the dog 52 is formed to provide a clamping cam 55 which bears against the presser bar when the rear end of the dog 52 is elevated by the abutment 51. This operates to grip the presser bar to elevate the same whenever the abutment 51 is elevated.

The presser bar 43 is depressed by a spring 54 surrounding the bar and bearing at its upper end against the head 15 and at its lower end against a collar 55 adjustable along the presser bar. A second spring 56 surrounds the presser bar bearing at its upper end against the collar 55 and at 35 its lower end against the collar 54. This spring serves to keep the collar 54 depressed against an upstanding stop 57, see Figure 6, mounted in the plate 11 and secured by a set screw 58 or other suitable fastener.

As the collar 54 is normally slidable along the presser bar so long as the abutment 51 is depressed and since the dog 52 is normally depressed by a spring 56, the presser bar may be raised and lowered independently of the action of the abutment 51. Whatever the position of the presser bar, as soon as said abutment is elevated, the dog 52 will operate to grip the presser bar and lift it a normal distance from its initial position at which the gripping occurs. The up and down movement of the abutment 51 is uniform as controlled by the cam 46. The presser foot, however, will be elevated initially in accordance with the thickness of the work operated upon. During such elevation the presser bar will slide upwardly through the collar 54. The lifting action of the dog 52 will now take place from this initial elevation. Accordingly, the presser bar will be lifted higher, the thicker the work operated upon. As previously described, the height of elevation of the presser bar controls the position of a stop 41 and through it the position of the cam 39. This mechanism, therefore, controls the height to which the up stroke of the needle bar is carried. As the total elevation of the presser bar is governed by the thickness of the work operated upon 65 the extent of the up stroke of the needle bar will be similarly governed and accordingly the needle will measure off a length of thread in accordance with the thickness of the work.

In order to provide adjustment for wear, the 70 crank disk 28 and the cam 46 are adjustably mounted on the shaft 10, being secured by set screws 149 and 150, see Figure 7. The disk 28 is provided with an off-set portion 151 adapted to enter the counter-bore 152 in the cam 46. These 75

two members 28 and 46 are both secured to the shaft 10 by the same key 153 which is preferably placed so that its center is opposite the rear face of the off-set 151 so that both members will have the same bearing on the key. By this arrangement the crank disk may be kept snugly up against the slide 22. Wear may be taken care of by loosening the set screw 149 and moving the disk on the shaft 10.

10 *Feeding mechanism*

The feeding mechanism of the awl is controlled by the feed cam 57 on the main shaft 10. This cam has the form shown in Figure 13 and is provided with a separate section 58 pivoted at 59 on the cam 57 and provided with an adjusting screw 60 threaded in a lug 61 on the section 58 and bearing against the hub 62 of the cam 57. The screw 60 provides adjustment to vary the throw of the cam. The section 58 may be secured in adjusted position by a clamping nut 63 or other suitable fastening.

The shaft 47 is journaled in a sleeve 64 clamped in a split socket in the bracket 13, one or more clamping screws 65 being provided in order to secure the same. This arrangement is such that as the sleeve 64 is slightly longer than its socket an endwise adjustment is provided in order to take up wear of the various parts and maintain a good fit.

30 Fixed to the shaft 47 is an arm 66 carrying a cam roller 67 adapted to run on the cam 57, 58. A spring 68 on the shaft 47 maintains the roll in engagement with the cam. The shaft 47 has fixed thereto a second arm 69 extending downwardly therefrom and pivoted at its lower end to a link 70. The link 70 has a pin 71 carrying a roller 72 adapted to run in a curved slot 73 formed in the upper portion of the presser foot 42. The pin 71 carries an awl shank 74 spring-pressed against the presser foot. The awl shank 74 carries a laterally extending cam 75 adapted to engage a guide pin 76 on the presser foot.

The action of this mechanism is as follows: The shaft 47 is rocked by the arm 66 in response to the movement of the cam 57, 58. This swings the arm 69 laterally, as indicated in dotted lines in Figure 10. By the shape of the slot 73 the first portion of the movement toward the left, Figure 10, of the arm 69 and the link 70 will carry the roller 72 downwardly along the inclined portion of the slot. This causes the awl 77 to pierce the work. Further movement of the link 70 carries the upper end of the awl shank to the left and the cam 75 now engages the pin 76 which in response to the movement toward the left throws the awl 77 to the left to execute the feeding movement. This movement, of course, is properly timed with the rest of the stitching mechanism by properly positioning the several cams on the shaft 10. The extent of the feeding movement is adjusted by adjusting the cam section 58 as already described.

Thread control

65 Fixed to the shaft 10 is a bevel gear 78 which incidentally carries a hand wheel 79 by which the shaft may be rotated by hand when desired. The bevelled gear 78 engages a similar gear 80 on a vertical shaft 81 suitably journaled in the standard 1. This shaft carries at its lower end a 70 bevel gear 82 engaging a corresponding gear 83 on a shaft 84 also journaled in the standard 1. The latter shaft is again connected through bevelled gears 85 and 86 to a shaft 87 journaled vertically in the standard 1 and extending upwardly 75 to the horn 88. The latter is suitably swivelled

on an extension 89 of the standard 1 so as to be rotatable in the usual manner. The shaft 87 is connected to drive a suitable chain of connections extending along the horn 88 so as to operate a whirl in the tip 90 of the horn. This whirl operating mechanism may be of any suitable type well known in the art and no detail description thereof will be necessary here.

5 Mounted on the horn 88 and between its swivel mounting on the extension 89 and the tip 90 is 10 a wax pot 91. The wax pot is provided on each side thereof with a forwardly extending rod 92 only one of which appears in the drawings. These rods engage sockets 93 one on each side of the horn 88. The wax pot itself is partly housed in a suitable opening in the lower portion of the horn 88. The mounting is thus removable 15 so that the wax pot may be slid from its housing, the rods 92 being slid out of their sockets 93. This movement takes place to the left Figure 1. Suitable latches may be provided to retain the wax pot in its operating position entering the horn as illustrated in Figure 1.

20 The wax pot has the general form shown in section in Figure 11 and provided with a cover 94 hinged at 95 to the rim of the pot. The cover is provided with a downwardly extending arm 96 carrying near its lower end a roller 97. A similar roller 98 may be arranged on the hinge pin 95. An outlet bushing 99 for the thread is also provided in the cover 94. This bushing is located within the horn 88, when the wax pot is in place, as may be seen from Figure 1. The outer face of the wax pot is provided with a pair of pins 100 over which the thread 101 may be passed as is indicated in Figure 12. A plate 102 pressed by a spring 103, whose tension may be adjusted by a thumb nut 104, bears against the thread, as shown in Figures 11 and 12, so as to provide a thread tension. The plate 102 is mounted on the pins 100 and the tensioning stud 105, being otherwise loose so that by drawing the upper end of the plate 102 to the left, Figure 11, the tension on the thread may be released. The thread 101 passes into the horn through the wax pot and from the bushing 99 directly up the horn and through the whirl in the usual manner as may be seen from Figures 1 and 11.

25 This arrangement places the wax pot in a position above the swivel of the horn and as close as possible to the tip 90. As a result the length of thread which extends between the wax pot and the tip 90 is reduced to a minimum. It is a custom with operators when the wax on the thread becomes gummy to draw out a length of thread equal to that extending from the tip of the horn down to the wax pot in order to provide freshly waxed thread for the sewing operation. The extent of thread thus extracted is usually cut off and wasted. Placing the wax pot as near as possible to the tip 90 the percentage of thread thus wasted is greatly reduced. As this thread is quite expensive, a considerable item of saving is effected thereby.

Control mechanism

30 Pivoted on a cross shaft 106 journaled in the foot of the standard 1 is a starting treadle 107 and a presser foot control treadle 108. The latter treadle is connected by a link 109 passing upwardly within the standard 1 to a lever 110 pivoted at 111 on the plate 11. The forward end of the lever 110 is arranged below a stop 112 adjustable in a clamp 113 clamped to the presser bar 43 and guided by an upright standard 114 fixed in the plate 11. The clamp 113 and the 35

guide 114 are similar to the clamp 11 and the guide 18 described hereinbefore. By pressing downwardly on the treadle 108 the rod 109 is pulled downwardly thereby rocking the lever 110 on its pivot, the forward end of which engages the stop 112 to lift the presser bar and with it the presser foot 42. Thus the operator may lift the presser foot to insert the work thereunder.

The treadle 107 is connected to an upwardly extending push rod 115 guided in a bracket 116 and tensioned downwardly by a compression spring 117 bearing at its upper end against the bracket 116 and at its lower end against a collar 118 adjustably fixed to the rod 115. The upper end of the rod 115 is pivoted to the horizontal arm 119 of a bell crank lever whose upwardly extending arm 120 is arranged to operate the clutch 14. Said clutch has a projection 121 normally engaging the end of the arm 120 so as to stop the shaft 110 in a position with the needle bar raised. Extending axially through the clutch 14 is a latch 122, spring-pressed toward the right, Figure 6 so that its protruding end may engage a lug 123 on the pulley 9 whereby to establish driving engagement to rotate the shaft 10. The pulley 9 has two lugs 123 placed diametrically opposite to one another. The latch 122 has a head 124 and the arm 120 has a tapered extension 125 arranged to pass under the head 124 so as to withdraw the latch 122 and break the driving connection. Lifting the rod 115 swings the arm 120 downwardly out of engagement with the projection 121 and carries the extension 125 out from under the head 124. This releases the latch 122 for engagement with the lug 123 so as to establish driving connection with the pulley 9 which rotates continuously. The latch 122 will engage one or the other of the two lugs 123. When the machine is to be stopped the treadle 107 is released and the rod 115 is lowered. This permits the arm 120 to return to normal position. As the clutch 14 rotates, the extension 125 which projects considerably in advance of the rest of the arm enters under the head 124 and withdraws the latch 122 after which the projection 121 engages the abutment 126 to stop the machine in proper position.

The pulley 7 is made in two sections, as illustrated in Figure 4. Each section is generally conical in form but provided with radially arranged sockets 127, see Figure 3, leaving therebetween projections 128. These projections on the different sections of the pulley may be interlocked with each other in telescoping relation as indicated in Figure 4. One of these sections is secured to the pulley 5 which is slidable along the shaft 6 as already described. The pulley 7 thus forms a grooved pulley having a groove, the depth of which may be varied by sliding one of these sections toward or from the other. The belt 8 runs in the groove thus formed but the effective diameter at which the belt runs may be varied by crowding the two sections together or separating them from each other. The rod 115 carries an adjustable arm 129 adapted to engage one arm 130 of a bell crank pivoted at 131 on a suitable bracket on the standard 1. The other arm 132 of the bell crank is arranged as a fork to span the shaft 6 and bears against a washer 133 which in turn bears against the hub of a pulley 5. By raising the rod 115 by means of the treadle 107 the arm 132 will be swung to the left, Figure 1, so as to crowd the two sections of the pulley 7 together thereby narrowing the slot and forcing the belt 8 to climb to an increased diameter on said

pulley. An idler pulley 134 on a swinging arm 135 retained by a spring 136 controls the tension of the belt 8 during these changes. A suitable guard 137 may be mounted on the shaft 6 so as to prevent accidental contact with the pulley 7. 5

It will be noted that there is a certain degree of lost motion between the arms 129 and 130. This permits the rod 115 to be moved sufficiently to engage the clutch 14 before the arm 130 is engaged. Accordingly, by depressing the treadle 107 a short distance, the machine may be started and operated at a low speed. If a long seam is to be made the treadle may be further depressed and the machine is then speeded up so as to shorten the operation. It will be further noted 15 that upon releasing the treadle 107, the speed is first reduced by permitting the pulley sections to separate and thereafter the clutch 14 is released and the machine stopped. By thus reducing the speed before stopping the machine, the shock of 20 stopping is greatly reduced.

It will be seen, therefore, that this invention accomplishes its objects in providing a machine of simplified structure and more compact arrangement. The stitching mechanism is so arranged that the needle measures off a length of thread in accordance with the length of the stitch and in accordance also with the thickness of the work. The measuring of the thread in accordance with the thickness of the work is accomplished by cooperation of the needle bar and the presser foot and its connections so that the up stroke of the needle bar is extended in accordance with the amount the presser foot is raised by the work. At the same time the lowermost point to which the needle moves on the down stroke is retained fixed and a pause is provided in the movement of the needle at this lowermost point. The movement of the presser bar is so controlled that it has a normal amount 30 of lift during the feeding movement above the top of the work and the point at which this lift begins is raised in accordance with the thickness of the work so that said thickness is added to the normal amount of lift. This not only provides proper clearance for the presser foot, but this movement is carried over into the needle bar so as to set off the amount of thread in accordance with the thickness of the work. 35

Adjustments for wear are provided at all the 50 important points, namely, between the crank disk and the slide on the needle bar and also in the mounting of the feed shaft 47.

The arrangement for varying the speed renders the machine capable of high speed operation 55 on the work requiring longer seams, while at the same time a low speed of operation may be maintained when required. The increase in speed takes place only after the machine has been started to its normal low speed and conversely 60 after operating at a high speed, the speed is reduced before the clutch is operated to stop the machine. These arrangements provide for reducing the amount of strain on the various parts of the machine and thereby lengthening their life 65 accordingly.

The mounting of the wax pot close to the tip of the horn is also effective in saving thread as already described. This pot is bodily removable for refilling or cleaning. 70

The rod 159 shown in Figure 1 is arranged to operate the switch, not shown, which starts the motor 3.

While this invention has been described as applied to a specific design of machine, it will 75

be understood that this is for the purpose of illustrating the invention and is not intended to limit the same in any way as various other applications of the invention will be apparent to those skilled in the art on the basis of the accompanying specification.

It is further understood that various individual features or sub-combinations may be useful by themselves without reference to other features, or the complete machine and that the employment of such individual features, or sub-combinations, is contemplated by this invention and within the scope of the appended claims.

It is further obvious that various changes may be made, within the scope of the appended claims, in the details of construction without departing from the spirit of this invention; it is to be understood, therefore, that this invention is not limited to the specific details shown and/or described.

Having thus described the invention what is claimed is:

1. In a sewing machine of the character described, a needle bar, driving means therefor, a presser foot, releasable connections between said driving means and said needle bar adapted to limit the down-stroke thereof to a constant position, and means controlled by the said presser foot adapted to release said connections at variable points in the up-stroke of said needle bar, whereby said needle bar is adapted to measure a length of thread for each stitch in accordance with the thickness of the work as gaged by said presser foot.
2. In a sewing machine of the character described, a needle bar, driving means therefor, connections between said driving means and said needle bar adapted to limit the down-stroke thereof to a constant position and having means providing a pause in the movement of said needle bar in such position.

3. In a sewing machine of the character described, a needle bar, driving means therefor, a presser foot, connections between said driving means and said needle bar including a slide on the needle bar engaging said driving means, and a stop on the needle bar engageable by said slide.

4. In a sewing machine of the character described, a needle bar, driving means therefor, a presser foot, releasable connections between said driving means and said needle bar, means automatically controlling the release of said connections, and means for frictionally retaining said needle bar against movement.

5. In a sewing machine of the character described, a needle bar, driving means therefor having a crank, connections between said driving means and said needle bar including a slide on said needle bar in driving engagement with said crank, and means for adjusting said crank relatively to said slide.

6. In a sewing machine of the character described, a needle bar, driving means therefor having a crank, connections between said driving means and said needle bar, and means for progressively varying the speed of said needle bar.

7. In a sewing machine of the character described, a needle bar, driving means therefor having a crank, treadle connections between said driving means and said needle bar, and means controlled by said treadle for progressively varying the speed of said needle bar.

8. In a sewing machine of the character described, a needle bar, driving means therefor in-

cluding a main shaft, a clutch for operating said shaft, a treadle connected to control said clutch, and means controlled by said treadle for varying the speed of said shaft.

9. In a sewing machine of the character described, a needle bar, driving means therefor including a main shaft, a clutch for operating said shaft, means for varying the speed of said shaft, a treadle, and connections controlled by said treadle adapted for operation to first operate said clutch and thereafter increase the speed of said shaft.

10. In a sewing machine of the character described, a needle bar, driving means therefor including a main shaft, a clutch for operating said shaft, means for varying the speed of said shaft, a treadle, and connections controlled by said treadle adapted for operation to first reduce the speed of said shaft and thereafter release said clutch.

11. In a sewing machine of the character described, a needle bar, driving means therefor including a main shaft, a clutch for operating said shaft, a treadle connected to control said clutch, and means controlled by said treadle for varying the speed of said shaft including a pulley having mutually telescoping sections relatively adjustable to vary the effective driving diameter thereof.

12. In a sewing machine of the character described, a needle bar, driving means therefor, a horn adapted to support the work in cooperative relation with a needle in said bar and having a thread guide, a swivel mounting for said horn, a wax pot mounted to enter said horn between said mounting and said guide, and means for guiding the thread to enter the horn through said pot.

13. In a sewing machine of the character described, a needle bar, driving means therefor, a horn adapted to support the work in cooperative relation with a needle in said bar, and a wax pot slidably mounted on said horn.

14. In a sewing machine of the character described, a needle bar, driving means therefor, a horn adapted to support the work in cooperative relation with a needle in said bar, a wax pot mounted to enter said horn above its base, a tension release for the thread on said wax pot and means guiding the thread through said release and then into said horn through said wax pot.

15. In a sewing machine of the character described, a needle bar, driving means therefor, releasable connections between said driving means and said needle bar, and means for varying the point of release of said connections.

16. In a sewing machine of the character described, a needle bar, driving means therefor, a presser foot, releasable connections between said driving means and said needle bar, and means controlled by said presser foot for varying the point of release of said connections.

17. In a sewing machine of the character described, a needle bar, driving means therefor, connections between said driving means and said needle bar adapted to limit the down-stroke thereof to a constant position, and means retaining said needle bar in such position.

18. In a sewing machine of the character described, a needle bar, driving means therefor, connections between said driving means and said needle bar adapted to move the latter in its down-stroke to a constant position and to release the same in that position, and means retaining said needle bar in such position.

19. In a sewing machine of the character described, a needle bar, driving means therefor, a hollow horn adapted to support the work in cooperative relation with a needle in said bar, thread-controlling and waxing means outside of said horn, a part of said waxing means extending into

said horn, and means for guiding a thread through said controlling means to said waxing means to enter said horn directly through said waxing means.
